UNITED STATES PATENT OFFICE.

WYLLY W. ATKINSON, OF SAVANNAH, GEORGIA, ASSIGNOR, BY DIRECT AND MESNE ASSIGNMENTS, OF ONE-THIRD TO MICHAEL K. JONES, OF SAVANNAH, GEORGIA, AND ONE-THIRD TO W. H. MARTIN, OF SHEFFIELD, ALABAMA.

ATTACHMENT FOR BEDSTEADS.

No. 921,339.

Specification of Letters Patent. Patented May 11, 1909.

Application filed November 13, 1908. Serial No. 462,401.

To all whom it may concern:

Be it known that I, WYLLY W. ATKINSON, a citizen of the United States, and a resident of Savannah, in the county of Chatham and 5 State of Georgia, have invented a new and Improved Attachment for Bedsteads, of which the following is a full, clear, and exact description.

The purpose of this invention is to provide 10 novel means for rigidly connecting and supporting the head and foot portions of a metal bedstead for the purpose of displaying the same in a window or elsewhere, to enable a free inspection of these portions of a bedstead that is thus exhibited for sale.

The invention consists in the novel construction and combination of parts, as is hereinafter described and defined in the appended claims.

Reference is to be had to the accompanying drawings forming a part of this specification, in which similar characters of reference indicate corresponding parts in all the views.

Figure 1 is a perspective view of the device 25 applied for supporting the head and foot portions of a bedstead in an upright position; Fig. 2 is an enlarged perspective view of the attachment showing one side thereof; and Fig. 3 is a perspective view displaying the 30 opposite side of the device.

The improvement is employed in duplicate for supporting the portions A and B of a metal bedstead, spaced apart in parallel planes, each of said attachments comprising 35 the following details: A body piece 5 of a suitable length and that is rectangular in cross section, affords support to two clamps and means for longitudinally adjusting the clamps. To this end, two guide strips 6 are

40 secured on each vertical side wall of the body piece 5. Preferably one of the guide strips 6 on each side is placed near an end of the body piece, and the other one on the same side a suitable distance from the opposite end 45 thereof. The guide strips have their ends disposed flush with the upper and lower sides of the body piece, and near their ends a recess b is formed in each end portion on the side adjacent to the body piece.

50 Each of the two clamps before mentioned, and that are similar, consists of the following details: A jaw 7, that has a concaved gripping surface is adjustably supported opposite a similar concavity formed in a corre-

sponding end of the body piece 5 by the attachment thereto of a slidable frame, composed of two bars 7^a, that are secured by similar ends thereof upon the outer side of the jaw at the upper and lower ends of the same, the opposite ends of said frame bars 60 being secured upon the ends of a vertical cross bar 7^b that holds the bars 7^a spaced apart in parallel planes. The frame bars 7^a are loosely inserted within the respective recesses b, thus affording a slidable engagement of the jaws 7 with the body piece 5 at the opposite ends thereof. A toothed rack 8 is formed or secured upon one of the members 7^a for each slidable frame, said racks being placed on the inner edges of said frame 70 bars.

A shaft 9 is journaled in a transverse perforation of the body piece 5, formed near the center thereof, and upon one projecting end of the shaft, a spur gear 10 is secured, that is 75 engaged with a corresponding rack 8 at that side of the body piece, and is thus connected with one jaw 7.

Upon the opposite end portion of the shaft 9, a similar gear 11 is mounted and secured, 80 which is meshed with the rack 8 on the frame bar 7^a on the other jaw 7, and upon an extended end of the shaft a crank handle 12 is secured.

Upon the upper edge of one frame bar 7^a, 85 a ratchet-toothed rack 13 is secured, and upon the body piece 5 opposite said rack, a pawl 14 is pivoted and adapted for interlocking engagement between the teeth of the rack 13.

90 Two of the improved attachments are used for the connection and support of the head and foot portions of a bedstead.

In applying the device the pawl 14 on each attachment is swung away from a corresponding rack 13, and the crank handle 12 is turned in a proper direction for a divergence of each jaw 7 from a respective concaved end of the body piece 5, thus producing a gap between each jaw and the adjacent end of 100 the body piece.

The head portion A and the foot portion B of a bedstead that are to be connected by the improvement, are stood upright and near each other, so that the jaws 7 may be passed 105 around the respective upright posts of the bedstead, and the latter be embraced between said jaws and the opposite ends of the

body piece 5. When both attachments have been mounted upon the head and foot portions of the bedstead the crank handles 12 are rotated so as to retract the jaws 7 and cause them to forcibly press upon the posts with which they are in engagement. When the clamps are adjusted as explained, the pawls 14 are caused to interlock with the racks 13 and thus secure the attachments upon the bedstead, holding the head and foot portions thereof spaced apart parallel with each other.

As indicated in Figs. 2 and 3, the concavities in the jaws 7 and in the ends of the body piece 5, are lined with a pliable material *a* and *a'*, which will prevent the bed posts from being marred by contact of the attachments therewith.

It will be obvious that by a release of the pawl 14 and a turning movement of the crank handle 12 on each attachment in a direction that will slide the jaws 7 away from the ends of the body pieces 5, the bedstead head and foot portions A, B, will be released from the attachments.

Having thus described my invention, I claim as new and desire to secure by Letters Patent:

1. A bedstead attachment, comprising a body piece, jaws carried by the body piece and slideable toward and from each end thereof, and means for simultaneously moving the jaws.

2. A bedstead attachment, comprising a body piece jaws carried by the body piece and slideable toward and from the respective ends thereof, means for simultaneously moving the jaws, and means for securing the jaws when in adjusted position.

3. A bedstead attachment, comprising a body piece that is rectangular in cross sec-

tion and having its ends concaved, a concaved jaw for each end of the body piece, a frame secured on each jaw and slideable on a respective side of the body piece, means for sliding said frames simultaneously, and means for securing the frames when slid so as to draw the jaws toward each other.

4. A bedstead attachment, comprising a body piece that is rectangular in cross section and having its ends concaved in a vertical plane, a concaved jaw for each end of the body piece, a slideable frame consisting of two parallel bars secured by the respective ends on a corresponding jaw and spaced apart opposite the ends by a vertical frame bar, a toothed rack on one member of each frame that is slideable on a respective side of the body piece, a shaft rotatably mounted in a transverse perforation of the body piece, a spur gear on each end of said shaft and meshed with the respective racks, a crank handle on the shaft, a ratchet-toothed rack on the upper member of one frame, and a pawl pivoted on the body piece which may interlock with said rack and hold the jaws retracted.

5. A bedstead attachment, comprising a body piece, a jaw coöperating with each end of the body piece, a frame secured to each jaw and slideable on one side of the body piece, means for moving the frames simultaneously, and means for securing the frames with the jaws in adjusted position.

In testimony whereof I have signed my name to this specification in the presence of two subscribing witnesses.

WYLLY W. ATKINSON.
